UNITED STATES PATENT OFFICE.

ANDREW J. BRAMLETTE, OF DOWNEY, CALIFORNIA.

CLAY-CUTTING SAND-PUMP.

SPECIFICATION forming part of Letters Patent No. 727,072, dated May 5, 1903.

Application filed December 20, 1898. Serial No. 699,848. (No model.)

To all whom it may concern:

Be it known that I, ANDREW J. BRAMLETTE, residing at Downey, in the county of Los Angeles and State of California, have invented 5 a new and useful Clay-Cutting Sand-Pump, of which the following is a specification.

The object of my invention is to provide means whereby well-borers can make rapid progress in sinking through clay, soft shale, 10 or in solid formation and also in packed sand.

My invention includes the improved sand-pump and also the cutter with which to transform an ordinary sand-pump into a sand-pump embodying my invention.

15 The accompanying drawings illustrate my invention.

Figure 1 is a view, partly in vertical mid-section, of a sand-pump embodying my invention. Fig. 2 is a view of the bottom of my 20 newly-invented clay-cutting sand-pump. Fig. 3 is a perspective view of one of the cutters detached.

A indicates the barrel of an ordinary sand-pump, having the ring B at the bottom in the 25 ordinary manner.

C C C C indicate a plurality of cutters which are duplicates of each other. Any desired number of cutters may be used. In the drawings I have shown a sand-pump provided 30 with four cutters. These cutters project downward below the ring of the sand-pump and extend across beneath the ring. The lower portion c of each cutter is curved vertically—that is, in a vertical plane—and the 35 cutters are attached to the ring of the pump with all the cutters curving in the same direction, so that when the sand-pump is lowered to strike upon the bottom of the well the cutters will tend to cause a slight rotation of 40 the pump as the cutters are inserted into the earth at the bottom of the well. Then when the sand-pump is drawn up the cutters pull up that portion of the earth at the bottom of the well which is above the edge of the cutters, and by repetition of the vertical operation 45 of the sand-pump the material becomes cut into small pieces and passes on up through the valve and into the barrel of the sand-pump. The cutters widen downwardly toward 50 their inner edges, the flaring being on the inner edge c' of the cutter, the outer edge

c" of the cutter being in a plane which is practically parallel with the axis of the pump.

1 indicates a shoulder above the bit 2 of the cutter at the base of the shank 3, by which 55 the cutter is fastened to the ring. The shank 3 is preferably an angle-iron, being bent into an angle in cross-section, and the flange 3' thereof is provided with rivet-holes 4, through which are inserted the rivets 5, by which the 60 shank is riveted to the ring. The shoulder on the cutter is of such a depth that when the cutter is in place the edge of the ring will be in a vertical line above a point intermediate the ends of the cutting edge, thereby avoiding 65 the strain upon the cutter that would be caused by having the force applied at either end of the blade. This permits of the cutters being formed from very thin material, as almost the entire strain upon the cutter comes 70 in a vertical direction or endwise of the cutter. The upward taper of the inner edge of the cutter gives more room than would be the case if the cutter extended full width from the blade to the top, and yet does not weaken 75 it to any perceptible extent.

If desired, the lower end of the flange of the cutter may be bent or curved outward to fit the beveled edge of the ring and prevent the earth from lodging therein. By bending the 80 flange at substantially a right angle to the shank and securing it to the ring the blade of the cutter does not point directly toward the center or axis of the pump, but a little to one side of it, thereby causing a greater rotation 85 of the pump or drill at each stroke and also permitting of cutters being used that do not reach to the center of the pump, as the core or portion of earth between the ends of the cutters will be broken up by the action of the 90 peculiarly-formed cutters.

The improved sand-pump is provided with the ordinary valve V and is used in the same way as an ordinary sand-pump.

The cutters are to be made of different sizes 95 for different-sized sand-pumps and may be kept in stock by dealers and well-borers, and when the formation is such as to require their use the appropriate cutters will be riveted to the sand-pump to be used. By cutting the 100 rivets they may be removed to be replaced by new cutters when desired.

Now, having described my invention, what I claim as new, and desire to secure by Letters Patent, is—

1. A sand-pump comprising the barrel and ring; and a cutter consisting of a sheet of material, the lower end of which is curved vertically and the upper portion of the shank is flanged or angular in cross-section and the outer edge is shouldered toward the inner edge, said shoulder being seated against the ring and the shank fastened to the inside of the ring and barrel.
2. A cutter for sand-pumps comprising a

substantially flat sheet of material; the lower end or blade of which is tapered to an edge 15 and curved vertically and the upper portion or shank is flanged or angular in cross-section, the outer edge of the cutter being shouldered and the inner edge being inclined from the inner edge of the blade toward the upper 20 end of the shank.

ANDREW J. BRAMLETTE.
